TONGUE FOR SHUTTLES FOR LOOMS FOR
WEAVINGGustave Diederichs, Ste-Colombe-Les-Veinne-
on-the-Rhone, FranceApplication January 30, 1931, Serial No. 512,456,
and in France July 22, 1930

2 Claims. (Cl. 139—207)

This invention relates to improvements in tongues for shuttles for looms for weaving.

The object of the invention being to effect such improvements in the construction of the same as to greatly facilitate the introduction of pirns the diameters of which may vary, and to permit the ready removal and renewal of the pirn when required.

With the above and other objects in view, the invention consists in the construction, combination and arrangement of devices hereinafter described and claimed.

In the accompanying drawing,—

Fig. 1 is an axial view partly in section.

Fig. 2 is a detail view of the mounting of the spring on the ring, to an enlarged scale.

Fig. 3 is a transverse section on line 3—3 Fig. 2.

In accordance with my invention the spindle *a* of the tongue is fixed at one end to the head *e*, a sleeve *h* is mounted for rotation on the spindle at the point adjacent the head and its outer end bears against an annular stop shoulder *i* which extends around the spindle. A split ring *j* is arranged around the end portion of the sleeve next the head and is provided with a rivet *k* by which it is closed. A helical spring *b* which tapers from its center to its ends is arranged around the spindle, its outer end is attached securely to the spindle and its inner end *l* is connected to the sleeve and split ring by being fitted in a slot with which the split ring is provided, as shown.

Thus by rendering the ring *j* immovable by means of special apparatus and causing the head

e to turn the spindle *a* and the end *c* of the spring the latter is stretched and diametrically contracted which permits the ready introduction of the tube or pirn on to the spindle whatever its internal diameter may be.

By freeing the ring *j* the spring *b* relaxes and owing to the increase in the diameter of its convolutions ensures perfect rigidity of the tube on the spindle.

Having now particularly described and ascertained the nature of my said invention and in what manner the same is to be performed, I declare that what I claim is:

1. A shuttle tongue for looms, comprising a head, a spindle having one end attached to the head and a helical spring arranged around the spindle and increasing progressively in diameter from its outer end toward the head, said tongue also having means whereby relative rotary movement may be effected between the spring and the spindle to effect variations of diameter in the convolutions of the spring to facilitate the putting on of a pirn, and said spindle being provided on the end next the head with a sleeve which is revoluble thereon, and a split ring having closing means and clamped around the sleeve and to which the inner end of the spring is connected.

2. A shuttle tongue as claimed in claim 1 in which the spindle is provided with an annular stop shoulder extending therearound and against which the outer end of the sleeve bears.

GUSTAVE DIEDERICHS.
